UNITED STATES PATENT OFFICE.

WILLIAM WALLACE THOMPSON, OF ORIENT, NEW YORK.

CHECK-REIN ATTACHMENT.

SPECIFICATION forming part of Letters Patent No. 320,724, dated June 23, 1885.

Application filed April 23, 1885. (No model.)

To all whom it may concern:

Be it known that I, WILLIAM WALLACE THOMPSON, of the village of Orient, town of Southold, in the county of Suffolk and State of New York, have invented a certain new and useful Improvement in Check-Rein Attachments to be used upon Harnesses; and I do hereby declare the following to be a full, clear, and exact description of the invention, 5 such as will enable others skilled in the art to which it pertains to make and use it, reference being had to the accompanying drawings, which form part of the specification.

Figures 1 and 2 are views, taken at right angles to each other, of a device embodying my invention.

My improvement consists of a piece of leather strap or other material, *a*, which is doubled and fastened upon itself, being re-enforced at 10 each end by the copper or other rivets *b*. Through the leather and just upon the inside of these rivets are made the holes *c' c''*. Through *c'* is passed the check-rein *d*, while in *c''* is inserted the saddle-hook *e*.

Even the very heavy and expensive leather that has been heretofore used on this part of the harness has not been sufficiently strong to withstand the strain often put upon it; but by means of the re-enforcement and doubling in my improvement the use of expensive and thick leather is dispensed with and the breaking of the attachment is obviated.

What I claim as my invention, and desire to secure by Letters Patent, is—

In combination with a check-rein, the strap *a*, provided with the holes *c' c''*, doubled upon itself, and folded over the rivets *b*, and said rivets, substantially as shown.

In testimony that I claim the foregoing I have hereunto set my hand this 26th day of March, 1885.

WILLIAM WALLACE THOMPSON.

Witnesses:

G. TABOR THOMPSON,
JOHN B. YOUNG.
